BOX STRUCTURE

Joshua Meier, New Rochelle, N. Y.

Application February 4, 1937, Serial No. 123,963

2 Claims. (Cl. 229—41)

This invention relates to box structures, and particularly to boxes of the type generally used for the transportation and storage of hats, sweatshirts, scarfs, shoes, or other articles. More particularly it relates to a box, the walls of which may be removed, folded, and inserted within the bottom and top members to diminish the space required for storage and shipping of the empty container.

10 An object of the invention is to provide a box having side walls removably attached to the bottom, and readily foldable for insertion in that bottom.

Another object of the invention is to so proportion the top and bottom members of the box structure that they may, together, without using the foldable side walls, comprise a shallow box in which the foldable side walls may be stored. This shallow box may likewise be used for the 20 storage or shipping of other articles.

It will be seen that due to this usage of the top and bottom members, to form either a shallow or deep box, it is possible for a vendor to have at hand box structures which may be combined to form either shallow or deep boxes which, despite their varying dimensions, will be in other respects substantially identical.

Another object of the invention is to provide a box structure such as that indicated above in which the side walls may be made of transparent material such as cellulose acetate, thus facilitating the use of the box as a storage device, since the contents may be readily viewed without removing the cover.

35 A further object of the invention is to provide a box structure with transparent side walls in which the side wall panels are joined together without using cement.

Other objects and features of the invention will appear when the following specification is considered in connection with the annexed drawings, in which—

Figure 1 is a perspective view of the box as it would appear with the side walls removed, and inserted within the shallow box structure;

45 Figure 2 is a perspective view showing the manner of assembling the top, side walls, and bottom into a structure suitable for use as a hat box;

Figure 3 is a perspective view of the assembled hat box;

50 Figure 4 is a transverse, sectional view taken on the line 4—4 of Figure 1, showing how the side walls appear when folded and inserted in the shallow box;

55 Figure 5 is a plan view of the box bottom with the side walls folded and placed therein; and

Figure 6 is a fragmentary cross-section of the assembled box structure of Figure 3, showing the construction of the side wall portion of the box, and the mode of fastening the side walls to the upturned edges of the box bottom.

As shown in Figure 1, the top of the box 11 is of the usual square or rectangular form; it may be made of cardboard, or any other suitable material, preferably covered with a fabric in order to improve its appearance. The bottom 12 10 is likewise constructed of cardboard, or other suitable material, and is so proportioned that the upturned flanges thereof fit within the downwardly extended edges of the top member 11. This structure consisting of the top and bottom 15 alone is in itself complete, and forms a box which is useful for packaging small articles, for example, scarfs, gloves, etc. It also serves to contain the side wall structure of the completed hat box when that structure is folded in the manner 20 hereinafter described.

The upturned flanges of the bottom portion 12 have fastened thereto the female members 13 25 of snap fasteners of common form. The co-operating male members 14 of the snap fasteners are affixed, see Figure 2, to the lower portion of the side walls 18 of the box structure. The sides of the box structure comprise four members or panels 18 which are preferably made of transparent material, such as cellulose acetate, 30 joined together at their edges by the fabric strips 17 (see Figure 5). These joining strips 17 are inserted one on either side of the edges of adjacent transparent panels 18, and are sewed together by stitching which passes through the 35 panel. Although my invention makes it possible to construct my box without the use of cement, it will be understood that cement or adhesives may be used to fasten the joining strips or fabric strips to the side panels.

The top edge of each panel has folded thereover, and extending downwardly, a short distance from the edge, a fabric strip 19 the edges of which are similarly stitched together with the stitches passing through the panel or otherwise attached (Figure 2). At the bottom of the panels there is a fabric strip 15 which is folded around the edge of each panel, and extends a short distance upwardly, the edges of which are stitched together through the various panels. 45 There is also along the bottom edge of each panel 18 at the inside thereof a reinforcing strip 16 which may be of cardboard or other suitable material, and which is stitched to the strip 15 and to the panel. These reinforcing strips 16 50 55

serve to render the side wall structure somewhat rigid, and to assure sufficient strength in the side wall structure to support itself as well as the box top 11. Similar reinforcing strips may be used 5 along the tops of the side panels if necessary or desirable.

The fabric corner pieces 17 are of material which is sufficiently flexible so that it may be bent, and the side walls folded upon themselves 10 so that they occupy sufficiently small space to be inserted in the shallow box formed by the cover 11 and bottom 12 in the manner shown in Figure 4.

If the material of the side wall panels is very 15 thin acetate or other material having insufficient strength to support itself, the corner pieces 17 and the strips 19 may be of rigid material such as cardboard. In this case the pieces 17 will still be capable of bending along a line at the 20 corner, this being accomplished by scoring the cardboard, or by utilizing cardboards on each panel joined by fabric strips or by like expedients.

Due to the construction described the side wall 25 panels may be bent somewhat without permanently denting the acetate or other material of which they are formed, whereas in the usual structure of the present day, the acetate side walls are held rigidly in position and are readily 30 dented. In addition, this structure obviates the necessity for using any kind of cement as a joint between the acetate or other similar surfaces, and thus precludes the failure of such a joint.

A retailer who utilized the invention could have 35 on hand a large number of the shallow boxes formed from the bottom 12 and tops 11, and a small number of side wall structures, which side wall structures could be readily stored in a portion of the shallow boxes. If the customer bought 40 an article which was small enough to be packaged in the shallow box, that would be done. If,

on the other hand, a customer should purchase a hat or similar article, it would be necessary merely to remove the side wall structure from one of the boxes, open it out, insert it with its lower edges inside the flanges of the bottom 12, snap 5 the male and female members 13 and 14 of the snap fasteners together, place the article within the deep box thus formed, and place the cover 11 upon the box. The fasteners may be omitted altogether where the box is only to be used in 10 an upright position, or where the fit is sufficiently snug to hold the parts together. Such a snug fit may be provided by properly proportioning the parts, or by grooving and slotting.

While I have described a preferred embodiment of my invention, I desire not to be limited by this description, but solely by the appended claims.

What I seek to secure by United States Letters Patent is:

1. A box structure comprising side wall panels 20 of pliable, transparent material, flexible means for joining said panels along the side edges thereof, a bottom, means for detachably securing said panels to said bottom, strips of flexible 25 material for protecting the top and bottom edges of said panels, and reinforcing strips affixed to said panels along the bottom edges thereof to give rigidity to the structure.

2. A box structure comprising side wall panels 30 of pliable transparent material, flexible strips joining the panels at the side edges thereof, said strips being attached in pairs one on either side of each edge of the panels and stitched together through the panels, a strip of flexible material 35 folded over and stitched together through the top and bottom edges of the panels to protect said edges, and a reinforcing strip stitched to said bottom edges and their protecting strip to give rigidity to the structure.

JOSHUA MEIER.
